CLAIM

I claim the ornamental design for a lancet, as shown and described.

DESCRIPTION

FIG. 1 is a front perspective view of the lancet;

FIG. 2 is a front perspective view thereof, the lancet rotated 90 degrees about its longitudinal axis with respect to the position shown in FIG. 1;

FIG. 3 is a side elevational view thereof;

FIG. 4 is a front side elevational view thereof;

FIG. 5 is a rear side elevational view thereof;

FIG. 6 is another side elevational view thereof, the lancet rotated 90 degrees about its longitudinal axis with respect to the position shown in FIG. 3; and,

FIG. 7 is a rear perspective view thereof.
